(57) **CLAIM**

The ornamental design for a sledge hammer head, as shown and described.

DESCRIPTION

FIG. 1 is perspective view of a sledge hammer head of the present invention;

FIG. 2 is top plan view of the sledge hammer head of FIG. 1;

FIG. 3 is side view of the sledge hammer head of FIG. 1 as seen from the right hand side of FIG. 1;

FIG. 4 is a bottom plan view of the sledge hammer head of FIG. 1;

FIG. 5 is a side view of the sledge hammer head of FIG. 1 as seen from the left hand side of FIG. 1;

FIG. 6 is a rear view of the sledge hammer head of FIG. 1; and,

FIG. 7 is a front view of the sledge hammer head of FIG. 1. The broken line showings of the handle are for illustrative purposes only and form no part of the claimed design.
